ISAAC T. WINCHESTER, OF BOSTON, MASSACHUSETTS.

Letters Patent No. 87,610, dated March 9, 1869.

IMPROVEMENT IN HOT-AIR FURNACES.

The Schedule referred to in these Letters Patent and making part of the same.

To all whom it may concern:

Be it known that I, ISAAC T. WINCHESTER, of Boston, in the county of Suffolk, and State of Massachusetts, have invented certain Improvements in Hot-Air Furnaces, of which the following is a full, clear, and exact description, reference being had to the accompanying drawings, making part of this specification, in which—

Figure 1 is a perspective view of my improved furnace, the brick-work by which it is to be surrounded not being represented.

Figure 2 is a vertical section through the centre of the same.

Figure 3 is a horizontal section on the line xx of fig. 2.

Figure 4 is a vertical section on the line yy of fig. 1.

My invention consists in a series of independent tubes passing through and forming the sides of the fire-pot, the cold air entering at the bottom of these tubes, and, when heated, passing into the hot-air chamber above, thus greatly increasing the amount of radiating-surface, and, consequently, the heating-capacity of the furnace; and

My invention also consists in constructing the top of the furnace in the form of an inverted frustum of a cone, or of such other form as will cause the heated products of combustion to be deflected against, and adding to the heat of the upper ends of the tubes passing through and forming the sides of the fire-pot, this peculiar form of the top giving a constantly-increasing area of radiating-surface, as it approaches the hot-air chamber above; and

My invention also consists in an adjustable smoke-pipe, so fitted to the lowest portion of the top of the furnace, that it may be turned around in any direction, according to the position of the flue it is to enter, the pipe, by its close proximity to the fire, receiving and imparting additional heat; and, furthermore,

My invention consists in a box or trunk, placed over the upper ends of two or more of the tubes forming the sides of the fire-pot, in order to receive and concentrate the currents of hot air passing up these tubes, a single tube leading from the said box or trunk to an apartment remote from the furnace, by which construction the whole of the hot air accumulated within the box is forcibly driven to the desired point.

To enable others skilled in the art to understand and use my invention, I will proceed to describe the manner in which I have carried it out.

In the said drawings, A represents the exterior casing of the furnace, which is to be enclosed within suitable brick-work, as represented by red lines, figs. 1, 2, and 3, in the ordinary manner.

Within this casing A, and extending partially around it, is arranged a series of independent tubes, B, the lower ends of which pass through a plate, a , and open into the bottom of a chamber, C, between the casing A and the brick-work surrounding it, while the upper ends

of these tubes pass through a plate, b , and open into the upper portion of the chamber C (containing hot air) above, which supplies the several pipes leading to the apartments to be warmed.

These tubes pass vertically up through and form the sides of the fire-pot, excepting at its front, where the coal is admitted, a sufficient space being left between the tubes to allow of the free circulation of air around them, to prevent their being destroyed by the heat.

The air admitted by the cold-air box into the lower portion of the chamber C, passes up, through the tubes B, to the upper portion of the chamber C, the currents of air being heated in their upward passage through these tubes, the contact of the fire therewith serving to intensify the heat to a great degree.

D is the ash-pit, of smaller diameter than the casing A, to admit of the lower ends of the tubes B communicating with the lower portion of the chamber C.

The top, E, of the furnace is of the form of an inverted frustum of a cone, (see fig. 2,) in order that the heated products of combustion, as they impinge thereon, may be deflected against the upper ends of the tubes B, whereby the air passing through them is heated to a greater degree, the form of the top of the furnace presenting a constantly-increasing area of radiating-surface, as it rises toward the hot-air portion of the chamber C.

It is evident, that instead of making the top, E, of the furnace of the form as above described, its sides c may be slightly curved inward or outward, without departing from the spirit of my invention.

G is a smoke-pipe, which fits over a collar or flange, d , passing up from the centre of the top, E, of the furnace.

This smoke-pipe is not rigidly connected with the furnace, but is free to be turned upon the collar d , as a centre, to any direction toward the flue which it is to enter, thus avoiding the inconvenience and expense of forming elbows, incident to the old construction, where the smoke-pipe projects out from the side at a fixed point, the lower portion of the pipe, by being in close proximity to the fire, also affording more heating and radiating-surface.

In furnaces as heretofore constructed, a great difficulty has been experienced in heating apartments situated at one side of and at a distance from the furnace, owing to absence of any provision for concentrating the currents of hot air to the points desired.

Instead of allowing all of the hot air to pass up into the hot-air chamber, or upper portion of the chamber C, I enclose the tops of two or more tubes within a box, or trunk H, (see figs. 1 and 4,) the top of which is provided with a single opening, e , to which is fitted a pipe, leading to the apartment heretofore difficult to be heated.

By the construction above enumerated, several currents of hot air are united within the trunk H, and are forcibly driven, through its contracted outlet, up into

the pipe leading to the apartment, consequently creating an increased velocity to the ascent of the rarefied air.

Where my improvements are to be applied to a portable furnace, it is simply necessary to provide an additional metal casing, so as to surround the casing A, and enclose the top of the furnace, thus forming a hot-air chamber.

Claims.

What I claim as my invention, and desire to secure by Letters Patent, is—

A series of independent tubes, B, passing through

and forming the sides of the fire-pot of a furnace, as and for the purpose set forth.

Also, the adjustable smoke-pipe G, in combination with the top, E, of a furnace, to the lowest portion of which it is fitted, and upon which it turns as a centre, substantially as and for the purpose described.

Also, the box, or trunk H, in combination with two or more tubes, B, as and for the purpose set forth.

ISAAC T. WINCHESTER.
